TABLET-ARM CHAIR

William James Bargen, Waukegan, Ill., and Mathilda K.
Bargen, Twin Lakes, Wis.

Filed Mar. 30, 1961, Ser. No. 64,549

Term of patent 14 years

(Cl. D33—11)

FIG. 3

FIG. 4

FIGURE 1 is a front perspective view of a tablet-arm chair, showing our design.

FIGURE 2 is a top plan view of the frame portion.

FIGURE 3 is a side elevational view of the chair.

FIGURE 4 is a front elevational view of the frame of FIGURE 2.

The essential features of our design reside in those portions shown in full lines on the drawing.

We claim:

An ornamental design for a tablet-arm chair, as shown and described.
